UNITED STATES PATENT OFFICE.

GRANT HAMMOND, OF NEW HAVEN, CONNECTICUT, ASSIGNOR OF ONE-THIRD TO
ALVA C. WASHBURN, OF PITTSFIELD, MASSACHUSETTS, AND ONE-THIRD TO
FREDERICK G. CRANE, OF DALTON, MASSACHUSETTS.

FIREARM.

Application filed August 8, 1918. Serial No. 248,979.

To all whom it may concern:

Be it known that I, GRANT HAMMOND, a citizen of the United States, residing in New Haven, in the county of New Haven and 5 State of Connecticut, have invented a new and Improved Firearm, of which the following is a specification.

My invention relates to automatic firearms, and an object of said invention, among 10 others, is to produce a gun of simple construction that has a solid, locked breech at the instant of firing, thus enabling the maximum force of the explosive charge to be utilized; a gun with a minimum amount of 15 "kick," thus enabling its continued use without producing fatigue; a gun in which the barrel, sights, receiver and handle are all maintained rigidly secured together, thereby giving the weapon as great accuracy as 20 an ordinary pistol. I have also shown an improved mounting for the bolt return spring over that shown in my former application of Serial Number 204,921 filed December 1st, 1917, which gives freer exit for 25 the exploded shell without sacrificing the general method of removing the bolt so as to enable the barrel to be cleaned from the breech end without dismounting the gun.

One form of firearm embodying my invention and in the construction and use of which the objects herein set out, as well as others, 30 may be attained, is illustrated in the accompanying drawings, in which—

Figure 1 is a view in elevation of the left 35 side of the gun with a portion broken away, showing a vertical section through the breech-bolt.

Figure 2 is a view in side elevation of a portion of the part that is broken away in 40 Figure 1.

Figure 3 is a rear elevation of the bolt and a portion of the receiver.

Figure 4 is a view in elevation of the right side of the gun.

Figure 5 is a plan view of the handle.

Figure 6 is a sectional view on the lines 6—6 of Figures 4 and 5.

The barrel 1 is screwed into the receiver 2 in the ordinary manner. The receiver is 50 secured to the handle 3 by a T-slot connection 3^a. This method of attachment is similar to the construction used where the barrel and receiver have a slight recoil movement on the handle, but in the present construc-

tion the receiver is rigidly secured to the 55 handle by a spring pressed pin 4 having a lug 4^a engaging a corresponding recess in the receiver. By pressing in this pin the receiver may be slid forward and disengaged 60 from the handle.

The handle 3 has a chamber for the magazine 5 carrying the cartridges 6 and having the follower 7 and follower spring 8, all of common construction.

The structure also includes the following 65 parts: hammer 9, hammer spring 10, hammer spring thimble 11, sear 12, sear pivot pin and arm 13, sear bar 14, sear bar disconnector 15, trigger 16, front sight 17, rear sight 18, extractor 47 and ejector 48. These 70 parts are all in common use in gun construction and perform their usual functions.

One of the improvements of the construction herein shown consists in the method of locking the bolt 19 to the receiver 2 at 75 the time of firing. This is done by the bolt lock which consists of a pin 20 mounted to slide in a pocket 19^a on the underside of the bolt and transverse to its axis. This bolt lock is urged downward by a spring 21 80 which acts against a bolt lock pin 22 in the bolt lock, both said lock and pin being slotted for the firing pin 23. A retaining pin 24 holds the bolt lock in place while assembling. The construction of the bolt lock 85 so far described, is very similar to that shown in the application already referred to, the only difference, but that a very important one, being that the contacting surfaces 25 between the bolt lock and the receiver are cut at a slight angle. In the drawings this angle is almost imperceptible, it being only about six and one-half degrees.

It has been determined in mechanics that, 90 between metallic surfaces, an angle of five degrees will not slip under constant pressure. The proper angle here is approximately somewhere between six and seven degrees. By putting a rod in the barrel against the bolt and applying a weight it 100 will be found that the bolt, when the bolt lock is in place, will sustain an almost unlimited weight; in fact the parts would be crushed before the bolt lock would slip out. A quick blow or shock, however, will release the bolt lock and open the bolt. This is what it gets when a cartridge is fired. 105 By making this slight angle on the bolt stop

I have produced a shock-operated automatic gun. Moreover, as the bolt lock slips out, the shock seems to be absorbed and its full force is not felt by the person firing the gun.

5 There is no more "kick" felt than when the barrel and receiver are permitted to recoil on the handle and very materially less, in both cases, than when a straight bolt lock is used which does not permit the bolt to be released. The determining factors are the angle of the surfaces 25 and the length of their contact; the tension of the spring 21 and the tension of the bolt return spring 26—the weight of the bolt also affecting it 15 slightly. The angle of the contact surfaces and the distance the bolt lock has to move, are the chief things to be considered in adjusting the gun to function properly for a given powder charge.

20 The bolt return spring 26 is mounted in a hole 27 which is cut partly in the bolt and partly in the receiver and is held on a guide rod 28. The front end of this rod just barely enters a blind hole 29 in a boss 30 formed on the front end of the bolt. The rear end of the rod has flattened sides 31 which have a free fit in a correspondingly shaped opening in an ear 32 of a sleeve 33 which is mounted concentric with the bolt and which 35 also affords a guide for the firing pin. The rod 28 is provided with a stop or lug 34 on its bottom side just inside the ear 32 and it has a semi-circular cut 35 on its upper side. A linchpin 36, having a semicircular cut 37, extends crosswise of the receiver. This cut is in line with the guide rod when the linchpin is clear in. By pushing the rod 28 slightly forward so that its cut 35 is in alignment with the linchpin the pin can 40 be inserted or removed as desired, but when the lug 34 is back against the ear 32 the rod 28 enters the cut 37 and locks the linchpin in place.

45 On the back end of the rod 28, there is mounted a sleeve 38 having a head 39 provided with lugs 40 which straddle the stop lug 34 when the parts are in the position shown in Figure 1. The linchpin extends through a cut across said head and keeps the 50 sleeve 38 from turning on the rod 28. The bolt return spring 26 acts between the boss 30 of the bolt and the head 39 of the sleeve 38. The head 39 rests against the linchpin, taking the thrust of the bolt return spring. It will be seen that when the bolt lock is raised and the bolt is thrown back to the rear by the explosive charge, so that the bolt stop 19^b reaches the rear wall of the opening 2^a on the right hand side of the 55 receiver (Figure 4), that the bolt return spring will be put under tension, and as the rod 28 moves with the bolt, the chamber 41 in the receiver is left entirely unobstructed for the ejection of the empty shells.

60 The bolt spring, rod, &c., may be taken out

without removing the sleeve 33, when the bolt is out of the receiver, by pushing forward the rod 28 until it is disengaged from the ear 32—the fit of the rod 28 in the blind hole 29 being loose enough to permit a slight sidewise movement of the rear end of the rod.

In order to withdraw the bolt by hand to load the first shell or to eject a loaded shell, the bolt lock 20 has to be raised. This is effected by an idle pin 42 in the handle, which is acted on by the rear end of a lever 43, the lever being mounted in a suitable recess made for it in the left side of the handle and held in place by a pin 44. By pushing down on a checked or knurled thumb piece 45 on the front end of the lever 43 the bolt lock will be raised, when the bolt may be drawn back by grasping the knurled bolt lugs 46 which are provided for this purpose.

I claim—

1. In an automatic firearm the combination of a bolt with a receiver and a bolt return spring mounted in a longitudinal opening cut partially in said bolt and partially in said receiver, a rod mounted at its ends at the ends of the bolt, around which said spring is coiled, a sleeve slidable on said rod and serving as the fixed end bearing 90 for said spring, and an abutment for said sleeve mounted in said receiver.

2. In an automatic firearm the combination of a receiver with a bolt, a bolt return spring, a guide rod for said spring mounted 100 in said bolt, a sleeve slidable on said guide rod and adapted to take the end thrust of said spring, and a linchpin mounted in the side walls of said receiver and adapted to act as an abutment for said sleeve, said 105 linchpin and said guide rod being reversely cut away and said guide rod serving as a lock for said linchpin.

3. In an automatic firearm the combination of a receiver with a bolt, a bolt return 110 spring, a guide rod for said spring mounted in said bolt, the front end of said guide rod being held in a blind hole in a boss formed on the bolt, the rear end of said guide rod having flattened sides and carried in an opening 115 of similar shape in an ear at the rear end of said bolt, said guide rod having a stop lug adjacent to said ear and having a notch on the side opposite said lug, a sleeve slidable on said rod and adapted to take the end thrust of said spring as the bolt is opened, said sleeve having a head with two prongs which inclose the lug of said guide rod, a linchpin mounted in the side walls of said receiver and serving as an abutment for said 125 sleeve and having a notch to engage said guide rod, said linchpin being in register with the notch of said guide rod when said guide rod is pushed slightly forward, but being out of register with said notch when 130

said guide rod is in its normal rear position, whereby the guide rod locks the linchpin and the linchpin permits the free movement of the guide rod.

5. 4. In an automatic firearm the combination of a receiver with a bolt, a bolt return spring, a guide for said spring mounted in

said bolt and a transverse linchpin mounted in the side walls of said receiver, said guide rod being adapted to lock said linchpin and 10 said linchpin being adapted to serve as an abutment to take the thrust of said spring when the bolt is opened.

GRANT HAMMOND.
